SASH BALANCE

August Vichweger, New Paltz, N. Y., assignor to
 Grand Rapids Hardware Company, Grand
 Rapids, Mich., a corporation of Michigan

Application June 16, 1938, Serial No. 214,081

2 Claims. (CL. 16—197)

This invention relates to a sash balance of the type having a balance spring and a co-acting rotatable spirally threaded element.

It is aimed to provide a novel structure of this general character in which the spring is completely enclosed and in which the construction generally is more stable, simplified and efficient.

The more specific objects and advantages will become apparent from a consideration of the description following taken in connection with accompanying drawings illustrating an operative embodiment.

In said drawings:

15 Figure 1 is a view in elevation, partly broken away, showing my invention applied to window sashes mounted in a window frame;

Figure 2 is a detail view partly in section and partly in elevation, on an enlarged scale, of the uppermost corner portion of Figure 1;

20 Figure 3 is a view of the sash balance detached;

Figure 4 is a view primarily in vertical section through the upper portion of the sash balance;

Figure 5 is a view in central vertical section, 25 through the lower portion of the sash balance;

Figure 6 is a vertical sectional view taken on the plane of line 6—6 of Figure 4;

Figure 7 is a cross sectional view taken on the line 7—7 of Figure 5;

30 Figure 8 is a detail section taken on the line 8—8 of Figure 3;

Figure 9 is a detail section taken on the line 9—9 of Figure 5;

Figure 10 is a detail section taken on the line 35 10—10 of Figure 1;

Figure 11 is a front elevation, partly broken away, of the stationary or frame bracket to which the rotatable rod is screw threaded, and

Figure 12 is a detail perspective of the upper 40 sash bracket.

Referring specifically to the drawings wherein like reference characters designate like or similar parts, 10 designates upper and lower window sashes, slidably mounted in the usual way in a window frame 11. These parts are of conventional construction. The improved sash balances are suggested at 12. The sashes may initially be provided with these sash balances in lieu of sash weights and cords or the like, or they may be used as replacements for the usual balances and cords, in which event, such weights and cords are removed, and the devices 12 substituted therefor.

In carrying out the invention, a tubular rod is provided at 13 which is preferably made from a relatively narrow strip of metal or other ap-

propriate material which is coiled spirally, with the edges of the spirals overlapping as shown at 14 and the outer edges of which are turned outwardly to form a screw thread or flight 15, it being clear, if desired, that the tubular rod thus produced is swaged or deformed in its course of manufacture so that it will have a truly cylindrical bore and be substantially truly cylindrical on the exterior, aside from the flight 15. The metal of the tubular rod may be welded, soldered 10 or otherwise secured together at the overlapping portions 14 or be made of material sufficiently strong to remain in the shape described and shown without solder, welding or extraneous fastening.

Said rotatable tube or device 13 is preferably used in pairs, with one located in grooves 16, provided in the outer longitudinal edges of each sash and the tubular members co-act with and house suitably tensioned coil springs 17, the latter having their wire preferably of square or rectangular form in cross section whereby a flat exterior will be presented since the coils contact, and whereby kinking is avoided.

At the upper ends such devices 12 include attaching brackets 17' of angular form, the same having depending spaced apart branches 18 provided with openings 19, through which screws may be passed to secure the brackets to the sashes 10. A stud 20 depends from the bracket 17', being rigidly fastened thereto as through the upsetting of a rivet extension 21 about an opening 22 in the bracket. A bushing 23 is interposed between the stud and tube, the latter being journaled thereon, and the bushing being fixed as by means of a pin 24 to the stud. Such bushing has a longitudinally extending slot 25 into which a terminal 26 of the spring 17 extends and is thereby anchored.

The lower end of the spring 17 is fastened to the upper enlarged end 26' of a bushing 27 which is fixed to and rotates with the tubular rod 13 since the latter has projections or indentations at 28 depressed into openings 29 of the bushing 27. Such bushing 27 in turn is journaled on a 45 stud 30 which is rigidly fastened to a lower bracket 31 screwed or otherwise fastened as at 32 to the sash.

In order that the spring 17 may be placed under proper tension prior to installation of the balance and maintained under tension during its application to the window sash, bushing 27 is provided with a series of notches or recesses 32' and bracket 31 has an opening 33 therethrough adapted to register with any of said notches or 55

openings 32' so that by employing a removable pin 34 removably engageable in the recesses 32' and opening 33, the bracket 31 may be utilized as a crank to tension the spring 17, it being understood that in doing this the upper end of the spring is restrained from rotation by grasping the upper bracket 17'. Alternatively, of course, the member 31 could be grasped and the upper bracket 17' rotated to tension the spring. Following such tensioning, the brackets 17' and 31 are affixed to the sash and a bracket 35 (to be described) positioned and attached to the window frame in proper position. Then pin 34 is removed to enable operation of the sash balance.

15 The tubular rod 13 co-acts with a stationary bracket 35 adapted to be screwed at 36 rigidly to the window frame 11. The tubular rod 13 passes through an opening 31 provided in an offset portion or collar 38 of the bracket and such opening is enlarged to provide a spiral groove 29 in which the flight 15 travels in order to turn the tubular rod or rods 13 incidental to sliding of the sashes 10 and correspondingly control the tension of the spring or springs 17.

25 It will be noted that the spacing of the branches 18 enables the same to straddle the portion or collar 38.

Various changes may be resorted to provided they fall within the spirit and scope of the invention.

30 I claim as my invention:

1. A sash balance comprising a tubular rod having a spiral flight on the exterior thereof, a bracket through which the rod passes having a portion engaged by the flight to cause turning of the rod, a spring within the rod, means to anchor the spring at one end, means movable with the rod engaging the spring at the other end to tension it through turning of the rod, said rod comprising a strip coiled with its edges in overlapping relation, the outermost edge being flanged to provide said flight. 5

2. A sash balance comprising an elongated cylindrical member, formed of a ribbon of sheet metal helically wound with the edges of each convolution engaging the edges of adjacent convolutions, to form a closed cylindrical wall of uniform diameter, an edge of such ribbon being bent to an angle with the ribbon surface and thereby forming a helical flange protruding substantially from the surface of said wall, means for rotatably mounting said member along the vertical edge of a sash, means adapted to be fixed to the frame within which the sash is carried, for engaging said flange to cause rotation of said member upon sliding the sash, and spring means within 25 said member and having its ends so connected in respect to said member and its mounting that rotation of said member is promoted during raising of the sash and retarded during lowering thereof. 30

AUGUST VIEHWEGER.
